UNITED STATES PATENT OFFICE.

WILLIAM SHERMAN BROWN, OF KNOXVILLE, TENNESSEE.

LOCOMOTIVE VALVE-GEAR.

1,110,288.

Specification of Letters Patent.

Patented Sept. 8, 1914.

Application filed January 17, 1914. Serial No. 812,778.

To all whom it may concern:

Be it known that I, WILLIAM SHERMAN BROWN, a citizen of the United States, residing at Knoxville, in the county of Knox 5 and State of Tennessee, have invented a new and useful Improvement in Locomotive Valve-Gears, of which the following is a specification, reference being had to the accompanying drawing.

- 10 My improvement relates particularly to mechanism for transmitting motion from a steam locomotive drive wheel to the distributing valve which admits steam to the cylinder.
- 15 The object of the improvement is to provide a construction which is simple, has its parts accessibly located, and avoids irregularity of valve action due to lost motion or "pounding" at the crank or due to rising 20 or lowering of the drive wheel relative to the locomotive frame.

This improvement is a modification of or analogous to the mechanism described by my Letters Patent of the United States No. 25 1,033,532, granted July 23, 1912, and No. 1,076,406, granted October 21, 1913.

In the accompanying drawings Figure 1 is a side elevation, portions being broken away, showing my improvement applied to 30 one side of a locomotive; Fig. 2 is a plan of a portion of the mechanism shown by Fig. 1; Fig. 3 is a section on the line, 3—3, of Fig. 2, looking toward the right; Fig. 4 is a section on the line, 4—4, of Fig. 2, looking 35 toward the right; Fig. 5 is a plan of a bridge member on which the bell crank is supported and which forms a guide for another member; Fig. 6 is a side elevation of the member shown by Fig. 5; Fig. 7 is a 40 section on the line, 7—7, of Fig. 1, looking toward the left.

Referring to said drawings, 1, is the usual valve stem extending to the distributing valve (not shown). The usual horizontal 45 parallel cross-head guide bars, 2, are supported at their rear ends by the guide yoke extension, 3. The usual connecting rod or pitman, 4, is coupled to the usual main crank, 5, carried by a drive wheel, D. On 50 the main crank, 5, is rigidly mounted an auxiliary crank, 6, standing 90 degrees forward of the main crank. To said auxiliary crank is coupled one end of the auxiliary pitman rod, 7.

55 A bridge, B, is located above the frame,

A, and extends from the ordinary guide-yoke, 8, and guide-yoke extension, 3, to the cross beam or plate, 10, and is secured to said guide-yoke and to said cross-beam by means of bolts, 9. Said bridge is in the 60 form of a plate having its length horizontal and being turned to bring its long edges into an upright plane. At its rear end, the bridge has a lateral extension, 11, resting against the cross-beam, 10, and receiving 65 said bolts, 9. At its forward end the bridge has a transverse extension, 12, reaching to both sides of the body of the bridge and resting against the guide yoke, 8, and the guide yoke extension, 3, and receiving said 70 bolts, 9. The innermost of said bolts extends through the transverse extension, 12, and the guide yoke, 8, while the others of said bolts extend through the transverse extension, 12, and through the guide yoke, 75 8, and the guide yoke extension, 3. On the outer portion of the transverse extension, 12, and integral therewith is an ear, 13, which is directed rearward; and on the inner portion of said transverse extension is 80 another ear, 14, also directed rearward and located horizontally opposite the ear, 13. Each of said ears has a bearing, 15, receiving the ends of a shaft, 16. On said shaft is a bell crank or rocking member, F, preferably rotatable on said shaft, the latter being held immovably in its bearings. Said bell crank has two approximately horizontal arms, 17, and a depending arm, 18. The latter arm is coupled to the valve-stem, 1. 90 By rocking the bell crank, the valve stem is reciprocated.

An approximately upright transmission link, 19, has its upper end coupled to the arms, 17, the link being forked to receive 95 said rod and said arms, as shown in the drawings. Said arms, 17, are also forked to receive the upper ends of the transmission link, 19.

On the outer end of the wrist of the auxiliary crank, 6, outside of the auxiliary rod, 7, is an arm, 51, which extends across the axial line of the driver and the driver axle. In said axial line, said arm has a wrist, 52. Since said wrist is on said axial line, it rotates, instead of traveling in an orbit, when the drive wheel turns. Hence, for the purpose of serving as a support, said wrist is stationary relative to the driver, just as would be the case if the driver axle were ex- 100 105 110

tended. Said wrist, 52, extends through the rear end of a horizontal supporting bar, 53, the forward end of which bar is hinged to the lower end of a link, 54, the upper end of which is hinged to a bracket, 55, which bracket is secured to the ear, 13. The hinges at the upper and lower ends of the link, 54, are horizontal and transverse to the length of the locomotive. The lower end of said link is forked to receive the supporting bar and the bracket, 55, is forked to receive the upper end of said link. Rearward of the link, 54, is a link, 56, the lower end of which is forked to receive the supporting bar, 53, and is hinged thereto by means of a horizontal bolt, 57, extending through said link and said bar. The upper portion of said link rests flatwise against the bridge, B. A guide bar, 58, is located at the opposite side of said link and has its ends turned against the bridge and secured thereto by bolts, 59. The upper portion of said link may move forward and backward between the bridge and said guide bar, the bridge and said bar preventing side-wise movement of said link.

On the upper end of the link, 56, is a transverse bearing, 60, which receives a bolt or axle, 31. By rocking the link, 56, on its lower end, said bolt or axle, 31, is carried through a curved path or arc corresponding to the path or arc which is traversed by the slide-block in the gear of my above-mentioned Patent, No. 1,032,532. Because the link, 56, is thus rocked when the reversing mechanism is actuated, said link may be regarded as a rocking member.

Opposite the inner side of the link, 56, is an approximately upright fulcrum link, 30, having at its upper end a bearing, 62, through which extends the bolt or axle, 31. Said link, 30, is thus supported by said axle and the link, 56. The lower end of said link, 30, is coupled to the auxiliary pitman rod, 7, by means of a bolt, 32, extending horizontally and transversely through said rod in the upright plane in which lies the bolt, 57, the location of said bolt, 32, being taken when the auxiliary crank is on either the upper or the lower quarter. The bolt, 32, is preferably at the same elevation as the bolt, 57, which forms an axis for the lower end of the link, 56. The bolt, 32, constitutes a fulcrum for the auxiliary rod and the link, 30, is termed a fulcrum link because it supports said fulcrum.

The forward end of an auxiliary reach rod, 33, is coupled to the bolt or axle, 31, the reach rod being forked to extend to opposite sides of the bearings, 60 and 62, the axle, 31, extending through the arms of said fork. The rear end of said auxiliary reach rod is coupled to an upright arm, 34, which is rigid on the rock-shaft 35, which shaft is supported in bearings, 36. On said rock-shaft 65 is an arm, 37, to which is coupled a rod, 38,

which is in turn coupled to the ordinary reversing lever, 39, working on a sector or quadrant, 40.

In operation, the link, 56, is set to bring its upper end into any desired position in its curved path, this being done by means of the reversing lever; and while said link is so set, the fulcrum link, 30, oscillates on the upper end of said link, 56, (on the axle, 31,) during each reciprocation of the auxiliary pitman rod, the axis of the bolt, 32, moving in an arc in which lies the axis to which the path of the upper end of the link, 56, or the axle, 31, is concentric. And, as above indicated, the distance between the wrist of the auxiliary crank, 6, and the bolt, 32, is such as to bring the axis of said bolt into the axis of the arc path of the upper end of the link, 56, when said auxiliary crank is on the upper or the lower quarter, at which time the main crank is on either the front or the rear quarter. In Fig. 1 the main crank is shown on the rear quarter, the auxiliary crank being on the top quarter. During each such reciprocation, said auxiliary pitman rod rocks bodily with the axis of the bolt, 32, as a fulcrum. This involves the rising and falling of the forward end of said auxiliary rod, and during such movement of said end of said rod, the transmission link, 19, is forced up and down and such movement of said link causes the rocking of the bell crank, F, which causes the reciprocation of the valve stem, 1.

Under normal conditions, the relation of the auxiliary crank, auxiliary pitman rod, the link, 19, the bell crank, and the valve stem remains unchanged and there is uniformity of operation of the bell crank and the valve stem, even if it be assumed that the curved path or arc traversed by the upper end of the fulcrum link, 30, during reversal, remains at the same elevation, as is the case when the support for said end of said link, 30, is supported entirely from the locomotive frame, A. But whenever by jolting or swaying or running on track curves, the relative elevation of the driver and the frame, A, is changed, the relation between the auxiliary rod and the transmission link, 19, on the one hand, to the bell crank and the valve stem, on the other hand, is changed. If, for example, the driver is lowered, the rear end of the auxiliary rod takes a lower position, and the forward end of said rod and the link, 19, takes a higher position, whereby the paths of the valve stem and the valve are moved rearward from the normal; and if the driver rises relative to the frame, A, the rear end of the auxiliary rod is lifted and its forward end and the link, 19, are lowered, whereby the paths of the valve stem and the valve are shifted forward from the normal. This is due to the fact that, while the reversing lever is set in any given

position, the path of the auxiliary rod fulcrum (the bolt, 32) does not change elevation and the orbital path of the rear end of the auxiliary rod changes elevation. This 5 may be understood by assuming that the auxiliary rod is detached from the locomotive and is pivoted on a fixed horizontal bolt occupying the position of the bolt, 32, and that the rod is brought into the horizontal 10 position and that its rear or long end is then moved up and down equal distances above and below a horizontal line cutting the fulcrum bolt. Such movement will cause the movement of the forward or short end of 15 said rod through equal distances above and below said horizontal line. But, if the path of the rear end of said rod be changed so that its middle is below said horizontal line, then the path of the forward or short end 20 of said rod will be proportionally above said horizontal line.

By means of my improvement, the elevation 25 of the auxiliary rod fulcrum is varied proportionally to the variation of elevation of the driver relative to the frame, A. In other words, the arc in which the auxiliary rod fulcrum reciprocates when the reversing lever has been set in a chosen position, is raised and lowered proportionally to 30 the rising and falling of the driver relative to the frame, A.

This is accomplished by supporting said fulcrum on the supporting bar, 53, and allowing the rear end of said bar to take the 35 up and down movements of the driver. The wrist, 52, on the arm, 51, as already described, is the axial line of the driver and is, therefore, without orbital movement relative to said axial line and only moves simultaneously with and in the same paths as said axial line. Said wrist supports the rear end 40 of said bar.

Hence said end of said bar moves up and down with the driver irrespective of the 45 movements of the frame, A. The forward end of the supporting bar may be regarded, for the present, as hinged to a fixed support on the frame, such hinge being at the lower end of the link, 54, the hinge at the upper 50 end of said link, 5, being, for the present, ignored. Hence, during changes in the relative elevation of the driver, the rear end of the supporting bar rises or falls, relative to the frame, while the forward end of said

55 supporting bar remains stationary relative to the frame. And when the orbital path of the rear end of the auxiliary rod, is raised or lowered, the rear end of the supporting bar is shifted in the same direction and 60 equally far. If, for example, the orbital path of the auxiliary rod is raised one-half an inch, the rear end of the supporting bar is raised one-half an inch. The rising of the rear end of the supporting bar causes the 65 lifting of the portion of said bar which sup-

ports the link, 56, and said link supports the fulcrum link, 30, which supports the fulcrum (the bolt 32), and consequently said fulcrum is lifted in unison with the portion of the supporting bar which supports the 70 link, 56. The distance between the bolt, 57, and the lower end of the link, 54, being the same as the distance between the bolt, 32, and the lower end of the transmission link, 19, it follows that rising or falling of the 75 bolts, 57, and the fulcrum bolt, 32, are equal. When the elevation of the driver relative to the frame, A, is changed, the elevation of the auxiliary rod fulcrum (the bolt 32) is proportionally changed in the same direction, so that the elevation of the path of the forward end of the auxiliary rod remains unchanged.

The essential point is to avoid allowing the relative rising or falling of the driver 85 to cause the rise or fall of the forward end of the auxiliary rod. This is accomplished by providing for the turning of the auxiliary rod on the hinge whereby said rod is secured to the transmission link. During 90 the rising and falling of the drive wheel, the supporting bar also turns on the hinge by which its forward end is secured. Said hinge is substantially in alignment with the hinge by which the forward end of the 95 auxiliary rod is joined to the transmission link, and the supporting bar and the auxiliary rod are of substantially the same length, and the axis of the bolt, 57, by which the lower end of the link, 56, is coupled to 100 the supporting bar and the axis of the bolt, 32, by which the lower end of the fulcrum link, 30, is coupled to the auxiliary rod are at equal distances from the hinge line at the forward ends of the supporting bar and the 105 auxiliary rod. Hence, if the lower end of the transmission link does not move up or down and the fulcrum link is free to move up and down and the driver is moved up or down, the supporting link, 56, and the fulcrum link will move up or down simultaneously and through the same distance. By supporting the fulcrum link entirely on the supporting link, the fulcrum link is made to go up and down, through the proper 110 range to allow the auxiliary rod to turn on the lower end of the transmission link during the relative up and down movements of the drive wheel.

The hinge by which the link, 56, and the 115 bracket, 55, are joined, is ordinarily at rest; for it is intended that the axial line on which the bar, 53, and the wrist, 52, are joined is to be ordinarily the rest. If such axial line is at rest, then the bar, 53, is at 120 rest and there is no reason for movement of the link, 5, on its upper hinge. But when there is lost motion on the driver axle that will cause endwise movement of the bar, 53, according to the derangement of the driver 130

axle, then the upper hinge of the link, 54, permits such movement without strain or breakage. Said hinge also permits yielding when through any other abnormal movement there is endwise strain on the bar, 53.

The gear is reversed by throwing the reversing lever across the center in the usual manner, and the opening of the valve is varied by moving said lever nearer to and 10 farther from the center, this being accomplished by the aid of suitable notches (not shown) on the reversing lever sector. When said lever is on the center, the valve motion is reduced to the extent of the "lead."

15 I claim as my invention:

1. In a locomotive valve gear, the combination of reversing mechanism, a valve stem, a reciprocating transmission member in operative relation with said valve stem, a rod 20 having its rear end at the outside of the drive wheel and having an orbital path concentric to the drive wheel axis and being coupled to said transmission member, and a fulcrum member coupled to said rod, and a 25 supporting member for said fulcrum member, said supporting member being in operative relation with said reversing mechanism for forward and rearward movement and with the drive wheel for up and down 30 movement relative to the locomotive frame, substantially as described.

2. In a locomotive valve gear, the combination of reversing mechanism, an auxiliary crank, an auxiliary rod coupled to said 35 crank, an approximately upright transmission link having its lower end coupled to the auxiliary rod and having its upper end in operative relation with the distributing valve, a fulcrum link having its lower end 40 coupled to said auxiliary rod, and means for supporting said fulcrum link at its upper end, said supporting means being in operative relation with said reversing mechanism for forward and rearward movement 45 and with the drive wheel for up and down movement relative to the locomotive frame, substantially as described.

3. In a locomotive valve gear, the combination of reversing mechanism, an auxiliary 50 crank, an auxiliary rod coupled to said crank, an approximately upright fulcrum link coupled by its lower end to the auxiliary rod between the ends of the latter and having its upper end coupled to said reversing 55 mechanism, an approximately upright transmission link having its lower end coupled to the forward end of the auxiliary rod and having its upper end in operative relation with the bell-crank, and means for supporting 60 said fulcrum link at its upper end, said supporting means being in operative relation with said reversing mechanism for forward and rearward movement and with the drive wheel for up and down movement

relative to the locomotive frame, substantially as described. 65

4. In a locomotive valve gear, the combination of reversing mechanism, an auxiliary crank, an auxiliary rod coupled to said crank, an approximately upright fulcrum link 70 coupled by its lower end to the auxiliary rod between the ends of the latter and having its upper end coupled to said reversing mechanism, an approximately upright transmission link having its lower end coupled 75 to the forward end of the auxiliary rod and having its upper end in operative relation with the bell-crank, a supporting bar having one end supported on the axial line of the driver and having its other end supported 80 by the locomotive frame, and means supported by said supporting bar and supporting said fulcrum link and being in operative relation with the reversing mechanism, substantially as described. 85

5. In a locomotive valve gear, the combination of reversing mechanism, an auxiliary crank, auxiliary rod coupled to said crank, an approximately upright fulcrum link coupled by its lower end to the auxiliary 90 rod between the ends of the latter and having its upper end coupled to said reversing mechanism, an approximately upright transmission link having its lower end coupled to the forward end of the auxiliary rod and 95 having its upper end in operative relation with the bell-crank, and an approximately upright rocking member supporting said fulcrum link and being in operative relation with a driver for up and down movement 100 proportional to the relative up movements of the driver, substantially as described.

6. In a locomotive valve gear, the combination of reversing mechanism, an auxiliary crank, an auxiliary rod coupled to said 105 crank, an approximately upright fulcrum link coupled by its lower end to the auxiliary rod between the ends of the latter and having its upper end coupled to said reversing mechanism, an approximately upright 110 transmission link having its lower end coupled to the forward end of the auxiliary rod and having its upper end in operative relation with the bell-crank, a supporting bar having one end supported on the axial 115 line of the driver and having its other end supported by the locomotive frame, and a rocking member supported by said supporting bar and supporting said fulcrum link and being in operative relation with the 120 reversing mechanism, substantially as described.

7. In a locomotive valve gear, the combination of a bell-crank, a valve stem in operative relation with the bell-crank, reversing mechanism, an auxiliary crank, an auxiliary rod coupled to said crank, an approximately upright fulcrum link coupled by its lower 125

end to the auxiliary rod between the ends of the latter and having its upper end coupled to said reversing mechanism, an approximately upright transmission link having its lower end coupled to the forward end of the auxiliary rod and having its upper end in operative relation with the bell-crank, and means for supporting said fulcrum link at its upper end, said supporting means being in operative relation with said reversing mechanism for forward and rearward movement and with the drive wheel for up and down movement relative to the locomotive frame, substantially as described.

8. In a locomotive valve gear, the combination of a bell-crank, a valve stem in operative relation with the bell crank, reversing mechanism, an auxiliary crank, an auxiliary rod coupled to said crank, an approximately upright fulcrum link coupled by its lower end of the auxiliary rod between the ends of the latter and having its upper end coupled to said reversing mechanism, an approximately upright transmission link having its lower end coupled to the forward end of the auxiliary rod and having its upper end in operative relation with the bell-crank, a supporting bar having one end supported on the axial line of the driver and having its other end supported by the locomotive frame, and means supported by said supporting bar and supporting said fulcrum link and being in operative relation with the reversing mechanism, substantially as described.

9. In a locomotive valve gear, the combination of a bell-crank, a valve stem in operative relation with the bell-crank, reversing mechanism, an auxiliary crank, an auxiliary rod coupled to said crank, an approximately upright fulcrum link coupled by its lower end to the auxiliary rod between the ends of the latter and having its upper end coupled to said reversing mechanism, an approximately upright transmission link having its lower end coupled to the forward end of the auxiliary rod and having its upper end in operative relation with the bell-crank, and an approximately upright rocking member supporting said fulcrum link and being in operative relation with the driver for up and down movement proportional to the relative up and down movements of the driver, substantially as described.

10. In a locomotive valve gear, the combination of a bell-crank, a valve stem in operative relation with the bell-crank, reversing mechanism, an auxiliary crank, an auxiliary rod coupled to said crank, an approximately upright fulcrum link coupled by its lower end to the auxiliary rod between the ends of the latter and having its upper

end coupled to said reversing mechanism, an approximately upright transmission link having its lower end coupled to the forward end of the auxiliary rod and having its upper end in operative relation with the bell-crank, a supporting bar having one end supported on the axial line of the driver and having its other end supported by the locomotive frame, and a rocking member supported by said supporting bar and supporting said fulcrum link and being in operative relation with the reversing mechanism, substantially as described.

11. In a locomotive valve gear, the combination of reversing mechanism, an auxiliary crank, a wrist supported by the auxiliary crank on the axial line of the driver, an auxiliary rod coupled to said crank, an approximately upright fulcrum link coupled by its lower end to the auxiliary rod between the ends of the latter and having its upper end coupled to said reversing mechanism, an approximately upright transmission link having its lower end coupled to the forward end of the auxiliary rod and having its upper end in operative relation with the distributing valve, and means for supporting said fulcrum link at its upper end, said supporting means being in operative relation with said reversing mechanism for forward and rearward movement and with said wrist for up and down movement relative to the locomotive frame, substantially as described.

12. In a locomotive valve gear, the combination of reversing mechanism, an auxiliary crank, a wrist supported by the auxiliary crank on the axial line of the driver, an auxiliary rod coupled to said crank, an approximately upright fulcrum link coupled by its lower end of the auxiliary rod between the ends of the latter and having its upper end coupled to said reversing mechanism, an approximately upright transmission link having its lower end coupled to the forward end of the auxiliary rod and having its upper end in operative relation with the distributing valve, a supporting bar having one end supported by said wrist and having its other end supported by the locomotive frame and means supported by said supporting bar for supporting said fulcrum link and being in operative relation with the reversing mechanism, substantially as described.

13. In a locomotive valve gear, the combination of reversing mechanism, an auxiliary crank, a wrist supported by the auxiliary crank in the axial line of the driver, an auxiliary rod coupled to said wrist, an approximately upright fulcrum link coupled by its lower end to the auxiliary rod between the ends of the latter and having its upper end coupled to said reversing

nism, the approximately upright transmission link having its lower end coupled to the forward end of the auxiliary rod and having its upper end in operative relation with the 5 distributing valve, an approximately upright rocking member supporting said fulcrum link and being in operative relation with said wrist for up and down movement proportional to the relative up and down movements of the driver, substantially as described.

14. In a locomotive valve gear, the combination of reversing mechanism, an auxiliary crank, a wrist supported by said crank 15 in the axial line of the driver, an auxiliary rod coupled to said crank, an approximately upright fulcrum link coupled by its lower end to the auxiliary rod between the ends of the latter and having its upper end coupled to said reversing mechanism, an approximately upright transmission link having its lower end coupled to the forward 20 end of the auxiliary rod and having its upper end in operative relation with the 25 distributing valve, a supporting bar having one end supported by said wrist and having its other end supported by the locomotive frame, and a rocking member supported by said supporting bar and supporting said fulcrum link and being in operative relation 30 with the reversing mechanism, substantially as described.

15. In a locomotive valve gear, the combination of reversing mechanism, an auxiliary 35 crank, an auxiliary rod coupled to said crank, an approximately upright fulcrum link coupled by its lower end to the auxiliary rod between the ends of the latter and having its upper end coupled to said reversing mechanism, an approximately upright transmission link having its lower end coupled to the forward end of the auxiliary rod and having its upper end in operative relation with the distributing valve, a supporting bar having one end supported on the axial line of the driver and having its other end supported by the locomotive frame to permit endwise movement

and to prevent lateral movement relative 50 to the locomotive frame, and means supported by said supporting bar and supporting said fulcrum link and being in operative relation with the reversing mechanism, substantially as described.

16. In a locomotive valve gear, the combination of reversing mechanism, an auxiliary crank, an auxiliary rod coupled to said crank, an approximately upright transmission link having its lower end coupled to the auxiliary rod having its upper end in operative relation with the distributing valve, a fulcrum link having its lower end coupled to said auxiliary rod, a supporting bar having one end supported on the axial line of the driver and having its other end supported by the locomotive frame, and means supporting a link coupled to the other end of said bar, and a bracket coupled to said link and to the locomotive frame, substantially as described.

17. In a locomotive valve gear, the combination of reversing mechanism, an auxiliary crank, an auxiliary rod, coupled to said crank, an approximately upright transmission link having its lower end coupled to the forward end of the auxiliary rod and having its upper end in operative relation with the valve stem, means applied to the auxiliary rod and traveling therewith and forming a fulcrum for said rod, and means for holding said fulcrum means to an arc path, and means in operative relation with the drive wheel for changing the elevation of said holding means proportionally to changes in elevation of the drive wheel, whereby the elevation of said arc path is correspondingly changed, substantially as described.

In testimony whereof I have signed my name, in presence of two witnesses, this 15th day of January, in the year one thousand nine hundred and fourteen.

WILLIAM SHERMAN BROWN.
